UNITED STATES PATENT OFFICE.

ORLANDO R. ERWIN, OF NEW YORK, N. Y., AND HAROLD V. GLOS, OF CHICAGO, ILLINOIS, ASSIGNORS TO FOAMITE FIREFOAM COMPANY, OF NEW YORK, N. Y., A CORPORATION OF DELAWARE.

FIRE-EXTINGUISHING DEVICE.

1,401,328.

Specification of Letters Patent. Patented Dec. 27, 1921.

Application filed December 10, 1920. Serial No. 429,639.

To all whom it may concern:

Be it known that we, ORLANDO R. ERWIN and HAROLD V. GLOS, citizens of the United States, and residents, respectively, of New York city, in the county of Queens and State of New York, and Chicago, in the county of Cook and State of Illinois, respectively, have invented certain new and useful Improvements in Fire-Extinguishing Devices, of which the following is a specification.

Our invention relates generally to a fire extinguishing device, and more particularly to a receptacle for containing a fire extinguishing charge and has special reference to the provision of a receptacle of the character referred to which may be conveniently mounted in a receptacle holder for ready access and which may be easily manipulated for discharging the contents of the receptacle in case of fire.

It has been found desirable in the art of fire extinguishers to provide a receptacle for a fire extinguishing charge suitable for convenient access in a conveyance such as an automobile, motor truck, motor boat, or aeroplane, which shall combine the characteristics of being of relatively small compass, being conveniently mounted for easy access and manipulation in cases of fire emergencies, having no interior operating parts in order to eliminate any chances of failure to operate and of being made of the fewest of parts for facility of operation in both charging and discharging, and for cheapness of manufacture.

The principal objects of our invention therefore involve, in addition to the provision of a receptacle and a holder therefor having the above mentioned characteristics; the further provision of a novel receptacle of the class referred to in which the fire extinguishing charge is held in a container, which charge is intended to be poured into a dispensing cup mounted on the container and then dashed from the dispensing cup on to the fire, the container and the cup being so constructed and arranged as to be easily mounted on and demounted from a holder associated therewith.

To the accomplishment of the foregoing and such other objects as may hereinafter appear, our invention consists in the ele-

ments and their relation one to the other, as hereinafter particularly described and then sought to be defined in the claims, reference being had to the accompanying drawings showing a preferred embodiment of our invention and in which—

Figure 1 is a side elevational view of the receptacle and the holder therefor, parts being shown in section to disclose the interior construction thereof,

Fig. 2 is a right end view of the same, and
Fig. 3 is a left end view of the same.

Means is provided for holding a fire extinguishing charge such, for example, as carbon tetrachlorid, which comprises preferably a container designated generally as 5, having in its preferred form a body portion 6 of relatively wide diameter and a closure end 7 of relatively small diameter, said container being preferably transparent and made of glass or other fragile transparent material and being of the size to hold, for example, a quart of fire extinguishing charge, the container having preferably a dished bottom 8. Mounted over the neck portion 7 is a cap 9, said cap defining a socket 10 in which is mounted the closure means for the container, said closure means consisting preferably of a cylindrical stopper 11 adapted to be inserted in the neck of the container and a disk stopper 12 adapted to fit between the top of the neck and the cap 9, the said stoppers being of any desirable material, such as cork or rubber and being retained in the socket 10, preferably by being fitted over a shank 13 formed centrally and preferably integrally with the cap 9, said shank having a threaded end portion 14 receiving a nut 15, which is seated against the stopper 11, retaining the stoppers in fixed position in the said socket 10. The cap 9 is formed preferably integrally with fingers 16, which are adapted to be grasped by the hand of the operator to afford easy removal of the closure means from the neck of the container.

For the purpose of suitably supporting one end of the container, means is provided which preferably is made integral with the cap 9, said means consisting of a stud 17 which is adapted to be retained in the holder, said stud being provided with an

enlarged head 18 to prevent endwise movement in one direction of the container in the holder.

In the event of fire the carbon tetrachlorid charge in the container is adapted to be first poured into a dispensing cup and from the dispensing cup on to the fire. For convenience, a dispensing cup 19 is provided having a dished bottom 20 fitting 10 on the dished bottom 8 of the container, the cup being thus adapted to be mounted over the bottom end of the container, as clearly shown in the drawings.

Means is provided for indicating the location of the extinguisher at night or in dark places which consists of an illuminating means and preferably of a radium spotlight or radiolight 21 mounted on a rod 22 connected to the shank 13 in any desired 20 manner.

The container is intended to be mounted in any convenient part of the vehicle for ready access in case of fire. To this end means is provided for conveniently supporting the container, which means preferably 25 consists of a U-shaped holder 22' having end portions 23 and 24 respectively, this holder being adapted to be mounted on any convenient portion of the conveyance in any 30 desired manner, as shown in the drawings. To the bottom of the holder is attached a spring clamp bracket 25 adapted to encircle the body portion of the container and preferably the body portion of the cup 19 mounted 35 on the container, as shown in the drawings. End portion 24 is provided with a forked top 26, the stud 17 of the container being adapted to be mounted between the prongs of the fork, the closure end of the 40 container thus being easily demountable from the holder by a simple upward movement of the cap and stud from the forked member 26.

Means is provided to prevent endwise 45 movement of the receptacle in the holder, which consists of a threaded shank 27 rotatable in a tapped bore 28 formed in the end portion 23, the said shank being provided at one end with a head 29 suitably contoured to fit the dished bottom of cup 19, said shank being provided at the other end with a thumb piece 30 serving for convenient manipulation of the shank and its head.

In operation, in the event of fire emergencies, the radiant spotlight will readily indicate to the operator the position of the fire extinguishing device. The receptacle is removed from the holder by a simple upward pull of the said receptacle, freeing the 55 stud 17 from the forked end 26 and the body portion of the container from the spring clamp bracket 25, the container being then grasped in one hand and the cap 9 with the attached stoppers and spotlight removed by 60 grasping the fingers 16 of the cap with the

other hand and exerting an upward pull thereon. The carbon tetrachlorid charge in the container is then poured into the dispensing cup 19 and from the dispensing cup the charge is poured on to the fire. The 70 operator may then securely close the container with its remaining charge, if any, by replacing the cap and its attached stoppers and spotlight on the container, the cup being then replaced on the body of the container, the said container being then returned to the holder, as will be obvious. The receptacle being transparent, the liquid level can be seen at all times, thus indicating when refilling is necessary. Recharging may be 80 obviously done by an inexperienced person without the use of any tools and without the necessity of returning the device to the factory, as is the case with prior devices. The container, as will be apparent, is adapted 85 to be used as a hand grenade by removal of the cup 19 and by grasping the container at its neck and hurling the same and the contents on the fire, the fragile container breaking as a result of the impact, as will 90 be apparent, permitting the charge to spread over the fire.

While we have shown our device in the preferred form, it will be obvious that changes and modifications may be made in 95 the structure disclosed without departing from the spirit of the invention, defined in the following claims.

We claim:

1. In a fire extinguishing device, a container having an opening at one end, said container holding a fire extinguishing charge, a closure for said opening, illuminating means mounted in said container and connected to said closure and a dispensing 105 cup mounted on the other end of the container.

2. In a fire extinguishing device, a fluid container having an opening at one end, said container holding a fire extinguishing 110 charge, a closure for said opening, illuminating means mounted in said container and connected to said closure, said closure embodying provisions for engaging a support and a dispensing cup mounted on the other 115 end of the container.

3. In a fire extinguishing device, a fluid container having an opening at one end, a closure for said opening embodying means for engaging a support, a cup mounted on 120 the other end of said container and a holder for releasably supporting said container and said means.

4. A fire extinguishing device comprising a container having a body portion and a 125 neck portion, a closure for the neck portion embodying provisions for engaging a support, a dispensing cup mounted over said body portion opposed to the neck portion and a holder for said container comprising 130

an element for holding the body portion of the container and an element for supporting said provisions.

5. A fire extinguishing device comprising a container having a body portion and a neck portion, the said body portion being provided with a dished bottom, a closure for the neck portion embodying provisions for engaging a support, a dispensing cup also 10 having a dished bottom fitting the container bottom and mounted over said body portion and a holder for said container comprising an element for releasably holding the body

portion of the container, an element for releasably supporting said provisions and adjustable means coöperating with the dished bottom and the dispensing cup for retaining the container in the holder against endwise movement.

Signed by ORLANDO R. ERWIN at New York in the county of New York and State of New York this 15th day of November, A. D. 1920, and by HAROLD V. GLOS, at Chicago, Cook county, Illinois, Nov. 23rd, 1920.

ORLANDO R. ERWIN.
HAROLD V. GLOS.
